US00D892158S

(12) **United States Design Patent** (10) **Patent No.:** **US D892,158 S**
(45) **Date of Patent:** **** Aug. 4, 2020**

(54) **DISPLAY SCREEN OR PORTION THEREOF
WITH GRAPHICAL USER INTERFACE**

(71) Applicant: **Google LLC**, Mountain View, CA (US)

(72) Inventors: **Jan Jedrzejowicz**, San Francisco, CA (US); **Brynn Marie Evans**, San Francisco, CA (US); **Rebecca Gisoo Park Chiou**, San Francisco, CA (US)

(73) Assignee: **Google LLC**, Mountain View, CA (US)

(**) Term: **15 Years**

(21) Appl. No.: **29/662,478**

(22) Filed: **Sep. 5, 2018**

Related U.S. Application Data

(62) Division of application No. 29/581,585, filed on Oct. 20, 2016, now Pat. No. Des. 828,371.

(51) **LOC (12) Cl.** **14-04**

(52) **U.S. Cl.** **USPC** **D14/488; D14/485**

(57) **CLAIM**

The ornamental design for a display screen or portion thereof with graphical user interface, as shown and described.

DESCRIPTION

The patent or application file contains a least one drawing executed in color. Copies of this patent or patent application publication with color drawing(s) will be provided by the Office upon request and payment of the necessary fee.

The FIGURE is a front view of a display screen or portion thereof with graphical user interface showing our new design.

The broken lines form no part of the claimed design. The outer rectangle in broken lines is included to show an unclaimed portion of an example display screen and forms no part of the claimed design. The portions of the graphical user interface shown in broken lines form no part of the claimed design.

**1 Claim, 1 Drawing Sheet
(1 of 1 Drawing Sheet(s) Filed in Color)**
